Youngstown, Ohio

Application May 28, 1940, Serial No. 337,642

4 Claims. (Cl. 312—48)

This invention relates to a beverage dispenser.

The principal object of this invention is the provision of a beverage dispenser unit a plurality of which may be conveniently positioned in a refrigerated cabinet so that any one of a number of various kinds of bottled beverages may be dispensed therefrom upon the insertion of a coin and the movement of a selector dial.

A further object of the invention is the provision of a beverage dispensing unit wherein the bottled beverage to be dispensed is released and delivered instantly upon the insertion of a coin in an associated coin controlled mechanism.

A further object of the invention is the provision of a dispenser unit wherein mechanism is employed to intermittently advance a row of bottles or other suitable containers so as to keep the leading bottle or container in each unit in position for instantaneous release and delivery.

A further object of the invention is the provision of a beverage dispensing mechanism comprising a unit adapted to intermittently feed and dispense beverages in suitable containers and wherein the activating movement comprises a threaded screw carrying a pusher plate by means of which the beverage containers are advanced into dispensing position.

A further object of the invention is the provision of a bottled beverage dispensing unit the use of a plurality of which in a refrigerated dispensing cabinet insures the continuously satisfactory dispensing of beverages from the dispensing cabinet from at least some of the bottle dispensing units therein as irregularities or mechanical failure of one or two beverage dispensing units in no way affects the operation of the other units in the dispensing cabinet thus insuring the continuous service of the cabinet.

Specifically, the beverage dispenser shown and described herein comprises a unit mechanism a plurality of which may be positioned in a refrigerated cabinet and when electrically connected to a suitable coin slot mechanism and a selector mechanism will dispense selected beverages or flavors upon the insertion of a coin in the coin mechanism without delay, as the unit mechanism feeds the bottled beverages into dispensing position automatically whenever the leading bottle has been dispensed.

With the foregoing and other objects in view which will appear as the description proceeds, the invention resides in the combination and arrangement of parts and in the details of construction hereinafter described and claimed, it being understood that changes in the precise

embodiment of the invention herein disclosed, can be made within the scope of what is claimed without departing from the spirit of the invention.

The invention is illustrated in the accompanying drawing, wherein:

Figure 1 is a top plan view of a plurality of dispensing units showing in detail the arrangement of the bottle moving mechanism and the positioning of the bottles being dispensed. Parts of this view are broken away and broken lines in this view indicate the approximate position of a refrigerated cabinet wall.

Figure 2 is a cross sectional side elevation with parts broken away taken on lines 2—2 of Figure 1 and shows in detail the operating mechanism of one of the bottle dispensing units shown in Figure 1 together with the various allied parts. The broken lines indicate the approximate position of the refrigerated cabinet wall.

Figure 3 is a symbolic wiring diagram showing the wiring circuits necessary for the operation of five dispensing units positioned in a single refrigerated cabinet and controlled by a single selector switch and a single coin controlled mechanism.

By referring to the drawing and Figures 1 and 2 in particular it will be seen that the beverage dispenser comprises a plurality of individual dispensing units, a side elevation of one of which is shown in Figure 2, and three of which are shown in the top plan view in Figure 1. Broken lines 10 indicate the approximate wall position of the refrigerated cabinet, and cross members 11 positioned therein serve to support a plurality of individual dispensing units each of which comprises a motivating screw 12 partially enclosed in a suitable guard 13 immediately above a bottom plate 14 upon which a plurality of bottles may be slidably positioned. The guards 13 serve to position the bottles in an orderly row and a pusher plate 15 positioned on the screw 12 serves to advance the bottles from left to right or toward the dispensing portion which, in each unit, comprises a trap door 16 pivotally mounted on one of the supporting members 11 at the extreme right or forward end of the bottom plate 14. The trap door 16 is provided with a spring 17 about the pivot thereof so that it normally tends to remain in closed position as shown in solid lines in the drawing. Positioned immediately in under the bottom plate 14 and in operative relation to the trap door 16 there is a magnetic latch 18, the electro magnet coil of which is indicated by the numeral 19. The electrical

connection wires leading from this electro magnet coil 19 lead, as may be seen by referring to the symbolic diagram in Figure 3, through a selector switch 20 to the coin controlled switch 21 so that a coin inserted in the coin controlled switch 21 activates the magnetic latch 18 thus releasing the trap door 16 and dropping a bottle thereon into a delivery chute 22 as indicated in broken lines in Figure 2. It is obvious that as many delivery chutes as necessary may be employed and that they may all terminate in a single delivery outlet in the front or in any other convenient location of the dispensing cabinet 10. In order that bottles of beverages may be advanced so as to place another bottle in dispensing position on the trap door 16 a pressure switch 23 is positioned on a vertical partition 24 in the front of the dispenser unit so that an operating plate 25 thereof is released when the bottle on the trap door 16 is dropped, thus permitting the operating plate 25 to move outwardly as shown in dotted lines in Figure 2 and close the switch 23 which is electrically connected, as may be seen in the symbolic diagram in Figure 3, by means of wires to a power supply and electric motor 26. The motor is indirectly connected to the motivating screw 12 by means of a reduction gear assembly 27 and a flexible connection 28 so that the motivating screw 12 is revolved thereby, thus causing the pusher plate 15 to advance the row of bottles until the forwardmost bottle contacts the operating plate 25 of the switch 23 which, in turn, disconnects the motor 26 thus accurately and automatically positioning the next bottle in line upon the trap door 16.

In an average dispensing cabinet a number of individual dispensing units are positioned side by side and in these instances the supporting members 11 support the motivating screw 12 of each of the units by means of pillow blocks 29. In order that the bottle channels formed by the guards 13 may be refilled from time to time, the pusher plate 15 has been provided with a manually operated clutch 30 so that it may be released from engagement with the screw 12 and slid backwardly to permit the positioning of additional bottles in the dispensing line.

It will thus be seen that each dispensing unit comprises a bottom plate 14 and one or more guards 13 between which a plurality of bottles to be dispensed are positioned and further, that the motivating screw 12 in connection with the pusher plate 15 serves to advance the row of bottles into dispensing position depending upon the control of the pressure operated switch 23, the operating plate 25 of which contacts the bottle arriving in dispensing position and serves to disconnect the motor 26 so as to stop the advancement of the bottles in the dispensing unit. It will also be seen that an entirely separate electrical circuit activated by a coin controlled switch 21 and directed by means of a selector switch 20 serves to activate the magnetic latch 18 which effectively releases the trap door 16 and drops the bottle in dispensing position into a delivery chute 22 instantaneously upon the insertion of a coin in the coin switch 21. It is obvious that it may be necessary to incorporate delayed action switches in connection with the operation of the latch 18 so that continuous dispensing from a single dispensing unit will delay the operation of the switch 18 a short time so as to permit the motivating screw to advance the next bottle in line into delivery position.

It will thus be seen that a dispensing unit has

been provided which, when used singularly or in connection with a plurality of similar units in a refrigerated cabinet, will serve to accurately and rapidly dispense bottled beverages without the attention of an attendant and that in the event that any one of the dispensing units becomes inoperative the remaining units are unaffected and hence keep the dispensing cabinet in active operation at all times.

10. What we claim is:

1. A beverage dispensing unit wherein a plurality of beverage containers are slideably positioned in a horizontal row, motivating means for advancing the row of beverage containers comprising a motivating screw positioned at one side of the row of beverage containers, and a pusher plate engaging the said screw and the said beverage containers so that revolving motion of the said screw causes the pusher plate to move the row of beverage containers, a trap door beneath the position of the foremost beverage container, switch means positioned above the said trap door and adapted to be engaged by the foremost beverage container, the switch means adapted to control the movement of the said motivating screw, a latch normally retaining the said trap door in closed position, a spring adapted to normally retain the trap door in closed position, and remotely positioned switch means adapted to control the said latch.

2. In a beverage dispensing device comprising a refrigerated cabinet having a plurality of dispensing units positioned therein, each of the said dispensing units comprising a bottom plate,

35 a pair of guide members positioned thereabove so as to form a channel for the reception of a row of beverage containers, means for advancing the row of beverage containers, said means comprising a motivating screw positioned adjacent the said row of beverage containers and a pusher plate positioned in the said channel and engaging the said motivating screw, clutch means formed on the said pusher plate so as to permit the said pusher plate to be manually released from the said motivating screw and moved backwardly thereon, a pressure operated electrical switch positioned at the foremost end of the said channel and adapted to be operated by contact thereagainst of the foremost beverage container, the said electrical switch controlling a motor coupled to the said motivating screw, a trap door formed in the bottom plate beneath the pressure operated switch and underneath the foremost beverage container and independently operated latch means for releasing the said trap door so as to drop the foremost beverage container therethrough for delivery from the said dispensing cabinet.

3. In a beverage dispensing device the combination of a refrigerated cabinet and a plurality of beverage dispensing units positioned therein, each of the said beverage dispensing units comprising a bottom plate, a pair of spaced guide members positioned thereabove so as to form a channel for the reception of a row of beverage containers, a pusher plate positioned in the said channel and engaging the said motivating screw, a releasable clutch forming the means of engagement therefor so that the pusher plate may be released from the said motivating screw and moved backwardly thereupon, a pressure operated control member positioned at the foremost end of the said channel and adapted to be operated by contact of the foremost beverage container thereagainst, the said pressure operated

control member controlling a motor coupled to the said motivating screw, and a trap door formed in the bottom plate beneath the foremost beverage container, an electrically operated latch controlling the said trap door, a spring normally retaining the trap door in closed position and a remotely positioned electrical switch controlling the said electrically operated latch so that a beverage container on the trap door may be delivered from the row of beverage containers by manual operation of the said remotely positioned switch.

4. In a beverage dispensing unit wherein a plurality of beverage containers are slidably positioned in a row the combination of means 15 for advancing the row of beverage containers,

said means comprising a motivating screw positioned at one side of the said row of beverage containers, a pusher plate engaging the said screw so that revolving motion thereof causes the pusher plate to advance the row of beverage containers, and means for controlling the motion imparted to the said motivating screw, said means comprising a contact plate positioned in front of the foremost beverage container and adapted to be engaged thereby, and means for delivering the said beverage containers comprising a trap door beneath the position of the foremost beverage container and independent means for controlling the operation of the trap door.
